United States Patent [19]

Rogov

[11] Patent Number: Des. 363,064

[45] Date of Patent: **Oct. 10, 1995

[54] **TERMINAL ADAPTER FOR A COMPUTER INPUT/OUTPUT COMMUNICATIONS SUBSYSTEM**

[75] Inventor: **Vladymir Rogov**, San Diego, Calif.

[73] Assignee: **Systech Computer Corporation**, San Diego, Calif.

[**] Term: **14 Years**

[21] Appl. No.: **27,661**

[22] Filed: **Aug. 26, 1994**

[52] U.S. Cl. **D14/114**

CLAIM

The ornamental design for a terminal adapter for a computer input/output communications subsystem, as shown and described.

DESCRIPTION

FIG. 1 is a top, right side perspective view of a terminal adapter for a computer input/output communications subsystem showing my new design;

FIG. 2 is a right side elevational view thereof on an enlarged scale;

FIG. 3 is a left side elevational view thereof on an enlarged scale;

FIG. 4 is a top plan view thereof, on a reduced scale;

FIG. 5 is an end elevational view thereof, on a reduced scale, the opposite end is identical; and,

FIG. 6 is a bottom plan view thereof, on a reduced scale.
